United States Patent

Des. 236,200
Patented Aug. 5, 1975

236,200

MENU HOLDER

Robert A. Summers, 5 Coventry Drive,
Freehold, N.J. 07728

Filed Apr. 19, 1973, Ser. No. 352,564

Term of patent 14 years

Int. Cl. D7—06

U.S. Cl. D19—28

FIG. 1

FIG. 2

FIG. 3

FIG. 4

FIG. 5

FIG. 6

FIG. 1 is a top perspective view of a menu holder showing my new design in partially opened condition;

FIG. 2 is a top plan view in closed condition;

FIG. 3 is a left side elevational view thereof;

FIG. 4 is a front elevational view thereof;

FIG. 5 is a rear elevational view thereof; and

FIG. 6 is a bottom plan view.

I claim:

The ornamental design for a menu holder, as shown and described.
